UNITED STATES PATENT OFFICE.

LEON R. WATERMAN, OF FLUSHING, NEW YORK, ASSIGNOR TO THE TIME TABLE ADVERTISER, INC., OF NEW YORK, N. Y., A CORPORATION OF NEW YORK.

COMBINED TIME-TABLE, TICKET HOLDER, AND ADVERTISING DEVICE.

Application filed November 10, 1924. Serial No. 749,080.

This invention relates to holders for tickets, such as commutation and trip railroad tickets, and it is an object of the invention to provide a holder which is in the nature of a 5 folder to serve as an enclosing protector for the ticket when not in use and stored away in a pocket or wallet, and by which the ticket without removal from its holder may be readily presented to a conductor for observation 10 and punching, and to provide a holder for this purpose which is novel, simple and cheap in structure.

It is another object of the invention to combine with a ticket holder of this character a 15 time-table by printing thereon, preferably on the inner surface thereof, a schedule of the running time of trains between the points or stations for which the ticket is issued, said folder being adapted to have matter printed 20 thereon, preferably on the outer surface, whereby the holder may also serve as an advertising medium.

In carrying out the invention I provide a 25 sheet of material, preferably relatively stiff though flexible paper, and print on one surface thereof a schedule of the running time of trains, and print on the other surface matter, such as advertisements, and fold said sheet upon itself to form a folder, said sheet 30 being preferably folded so that the printed schedule will be on the inside. I attach to the inner surface of the sheet a strip or tab extending transversely thereof and between which strip and the folder a ticket is engaged 35 to hold the ticket along a marginal portion thereof, said strip or tab being arranged so that the ticket will extend in juxtaposed relation to one flap of the folder and when the folder is folded the ticket will be enclosed and 40 protected thereby. The strip or tab is arranged so that the ticket may be slid outward from the folder, or the folder and ticket may be bent or flexed laterally one from each other, for ready presentation to a conductor to 45 be observed and punched by him.

In the drawings accompanying and forming a part of this specification,

Figure 1 is a perspective view looking at the front of the device in closed condition.

50 Figure 2 is a perspective view of the holder shown in Figure 1 with a portion of one flap of the folder moved to open position to observe a schedule or other matter printed on the inner surface thereof; and

55 Figure 3 is a perspective view of the holder

shown in Figure 1 showing the holder in open condition and one flap and the ticket bent apart from each other to present the ticket to the conductor in position to be readily punched by him.

In carrying out the embodiment of the invention, a sheet of paper, preferably relatively stiff though flexible, is folded upon itself to form a folder having flaps 6', 7' and the running schedule of trains printed 60 on the inner surface and advertising matter on the outer surface thereof. To adapt the folder as a holder for a ticket T, such as a railroad commutation or trip ticket, issued for use between designated points or 65 stations on a railroad, a holding strip or tab 8 of transparent and flexible material, celluloid and the like having been found desirable for this purpose, whereby printed matter below said strip may be observed through 70 the same, is attached by staples 9 at the outer marginal portion of one of the flaps in the present instance flap 7 and at the portion of the folder adjacent the fold of the flaps to 75 extend parallel with said fold, a marginal portion of the ticket being engaged between said strip and the flap to hold the ticket by the folder, the engagement of the ticket beyond the strip being limited by the abutment of the edge of the ticket against the 80 fold of the flaps, or such engagement of the ticket may be limited by a staple 10 intermediate the ends of the strip. In this arrangement to facilitate the reading of the time table on the inner side of the fold below the ticket, and also to facilitate the presenting of the ticket to the conductor for inspection and punching, the flap 7' is arranged with a transverse weakened portion, 85 as by scoring, on a line parallel with the fold and spaced from the fold a distance substantially equal to the width of the strip, as at 11, whereby said flap 7' may be bent laterally on said scored line as shown in 90 Figure 2. The ticket is of less width and length than the flaps of the folder so that when the folder is folded the ticket will be 95 enclosed within and protected by the flaps.

100 While I have illustrated and described the folder as comprising two flaps it will be obvious that the folder may be composed of three or more flaps with the ticket-holding strap 8 attached to one of the flaps. It will also be understood that various modifications may be made in detail arrangement 105 110

of parts, and that portions of the invention may be used without others and come within the scope of the invention.

Having thus described my invention I 5 claim:

1. In a holder for railroad tickets, a folder comprising a sheet folded upon itself to divide the sheet into flaps and having printed thereon a schedule of the running time 10 of trains and having other printed matter thereon to adapt the folder as an advertising medium, and a strip of transparent material attached to the sheet with one edge extending transversely of and contiguous to 15 the fold for the engagement of a ticket between said strip and the folder, and said sheet arranged with a weakened portion to extend transversely and parallel to the fold and spaced from the fold a distance equal to 20 the width of the strip whereby said flap of the folder may be readily bent laterally for the presentation of the ticket for punching to the conductor.

2. In a combined time table and holder

for a railroad ticket, a folder comprising a 25 sheet folded upon itself to form a pair of flaps having printed thereon a schedule of the running time of trains and other printed matter thereon to adapt it as an advertising medium, a strip of transparent material attached to a flap of the folder with one edge adjacent to and extending parallel with the fold of the flaps of the folder for the engagement of a ticket between said strip and flap to hold the ticket at an edge portion 30 thereof, and the flap of the folder to which the strip is attached arranged with scoring in a line parallel with the fold of the flap and spaced a distance therefrom equal to the width of the strip to provide said flap 35 with a weakened portion to facilitate the bending of the flap on said scoring to readily present the ticket to and for punching by a conductor.

Signed at New York city, in the county of New York and State of New York this 3rd day of June, 1924.

LEON R. WATERMAN.
